United States Patent Office

Des. 174,157
Patented Mar. 8, 1955

174,157

FORK OR SIMILAR ARTICLE

Nord Bowlen, Greenfield, Mass., assignor to Rogers, Lunt
& Bowlen Company, Greenfield, Mass., a corporation
of Massachusetts

Application February 17, 1954, Serial No. 29,057

Term of patent 14 years

(Cl. D54—12)

Fig. 1.

Fig. 2.

Fig. 3.

Fig. 4.

To all whom it may concern:

Be it known that I, Nord Bowlen, a citizen of the United States, residing at Greenfield, in the county of Franklin and Commonwealth of Massachusetts, have invented a new, original, and ornamental Design for a Fork or Similar Article, of which the following is a specification, reference being had to the accompanying drawing, forming part thereof.

Fig. 1 is a plan view of a fork illustrating the design;

Fig. 2 is an enlarged cross section along line 2-2 of Fig. 1;

Fig. 3 is a cross section along line 3-3 of Fig. 1; and Fig. 4 is a side view of the fork.

I claim:

The ornamental design for a fork or similar article, substantially as shown.
